UNITED STATES PATENT OFFICE.

MILLER REESE HUTCHISON, OF BRONXVILLE, NEW YORK.

MECHANICALLY-ACTUATED ACOUSTIC APPARATUS AND METHOD.

No. 923,048.

Specification of Letters Patent.

Patented May 25, 1909.

Application filed March 14, 1906. Serial No. 305,933.

To all whom it may concern:

Be it known that I, MILLER REESE HUTCHISON, a citizen of the United States, and a resident of Bronxville, in the county of Westchester and State of New York, have invented certain new and useful Improvements in Mechanically-Actuated Acoustic Apparatus and Methods, of which the following is a specification.

10 This invention relates to signaling or alarm horns particularly such as are used on automobiles, fire engines, launches, steam boats, light houses, factories, etc.

15 My object is to produce a device of this type capable of utilizing as much power and of producing as loud a sound as may be desired.

20 Another object is to obviate the necessity for refinements of construction and adjustment usually found in devices of this class and also to insure reliable positive operation of the device, under all the exigencies of practical every day use.

25 In the accompanying illustration I have shown, more or less diagrammatically, sundry embodiments of my invention.

30 In this showing:—Figure 1 is a view, partly in section and partly in elevation, of a complete acoustic apparatus under the present invention; Fig. 2 is a diagrammatic illustration of a modification having different drive means; Fig. 3 is a view of an eccentrically mounted pitman having a lost-motion engagement with a diaphragm; Fig. 4 is 35 a view, partly in section, of the same structure taken at right angles to the view of Fig. 3; Fig. 5 is a detail view, partly in section, showing the mounting of the pitman in a rotary drive member; Fig. 6 is a detail view 40 showing positive engagement of a pitman with a diaphragm; Fig. 7 shows an alternative manner of connecting pitman and diaphragm; Fig. 8 shows still another alternative connection; and Fig. 9 shows a cam 45 actuated diaphragm.

The invention may be embodied in many different specific forms but I usually prefer to employ a horn 1 and some form of case, as 2, though any form of resonant amplifier 50 may be employed or may be omitted altogether, as may also the case 2. These parts of the device may be of any known or desired construction.

As shown in Fig. 1 the horn is screwed into

a nipple 3 in an end closing cap screwed on 55 to the case 2. The horn is secured by a set screw 5' and the end closure 4 may be provided with any desired locking means.

The vibrator for exciting the horn may be held in any desired way and may be a diaphragm 5, held by suitable washers 6^a, which may be clamped between the front end of the case 2 and the end closing cap 4.

The diaphragm is caused to execute its to and fro movements through a suitable mechanical connection, a preferred form of which is shown in Figs. 3, 4 and 5. As a source of power, I may utilize any reciprocating or rotary motor but preferably a rotary motor with a link and crank, or eccentric 70 or other device for changing rotary into reciprocating motion.

In Fig. 1 I have shown the link 6, mounted on the crank pin or eccentric 7, and connected to the diaphragm 5 through a pitman 75 8. The link 6 and the pitman 8 together form an articulated thrust member or element, rigid in the line of action. When this articulated thrust member is employed some form of guide such for instance as shown at 80 9 is necessary. This is held in position by a suitable support 10, which may be formed as a tight partition. In any case the support may be adjustable, as shown; and in the case of a tight partition, this serves to 85 vary the resonance space back of the diaphragm 5, so that it may operate as an adjustable resonator, in addition to serving its function as guide for the pitman 8.

The resonator partition is less necessary 90 in my present device because I am able to apply greater power to the diaphragm and thus make it less important in practice to have the refinements which are highly desirable in the arrangement of less positively acting devices of this type. I may use a simple link connection between the eccentric and the vibratory diaphragm 5 as shown in Figs. 3, 4 and 5. In such case the movement necessary for vibration of diaphragm 5 is provided by the adjustable crank pin 7 carried by the head 11 adjustable in groove 12 which is under cut as at 13 to fit said head. The crank pin presents a bearing surface eccentric to the drive member 11. The crank is clamped in the desired eccentric position by means of the sleeve 14 the annular collar 16 of which engages the

face of the rotary disk 15. It is forced into clamping relation therewith by means of the nut 17^a, thus binding the head 11 against the under cut portion 13 of groove 12. The 5 sleeve 14 serves as the journal for the link 6.

The disk 15 may be rotated in any desired manner from any desired source of power. As shown in Fig. 1 it is supported in a suitable standard 17 within the case 2 and is 10 connected by a flexible shaft 18, with a friction wheel 19, adapted to engage the flywheel or shaft or any other rotating part preferably rotated by the prime motor of the automobile or launch. Such rotating 15 part is diagrammatically indicated at 20.

The friction wheel 19 is arranged or constructed to have its movement controlled by the operator so that the diaphragm 5 may be vibrated and the horn sounded at 20 will. The friction wheel 19 may be mounted in a movable journal 21, for movement into and out of contact with 20. The journal 21 may be carried by a reciprocating member 22 slidably held in a guide 23 which may 25 be in the form of a bushing secured by a nut 24 as shown. A collar or other stop 25 may be employed to limit movement away from the driver and a spring 26 may be provided for normally holding the parts in retracted 30 position. A fixed brake shoe 27 may be arranged to bear upon 19 in the retracted position to prevent prolonged dying away effect of the sound in the horn when the power is shut off. The reciprocating member 22 is 35 provided with a head 28 arranged in a suitable position for control by the operator preferably in the floor 29 within reach of his foot.

In Fig. 2 I have shown another desirable means for causing and controlling the rotation of the disk 15 to agitate the diaphragm 5. In this arrangement the disk 15 is mounted upon the shaft of an electric motor 30 which may be mounted within a case 2 (Fig. 1) in any suitable manner. The motor 45 may be quite small and consume but little current and may have an operating voltage so low as to be readily supplied from the storage or other batteries used for igniting the engine or if desired a small generator 50 driven from any desired rotating point of the engine may be used as the source of power. Circuit leads 31, 32 connect the motor with any such source as, for instance, the battery indicated at 33 and there may be bridged 55 thereacross any desired number of circuit closers 34, the closure of any of which will serve to start the motor and sound the horn. An adjustable impedance 35, may be included in this circuit and may be either an 60 inductive or an ohmic resistance or both and may be designed and regulated either to limit the maximum normal operating current or to prevent too sudden and too great instantaneous current at starting or to accomplish both functions. This form of

drive is more specifically shown, described and claimed in my application Serial No. 457,710.

The reciprocating movement imparted to the link 6 or pitman 8, whether from one of 70 the above described sources of power or from any other desired source, may be applied to the vibrating diaphragm in a variety of ways, either by tapping impact thereon or by positive forced vibration thereof or by 75 partly forced and partly free elastic vibration. While the impact or engagement may be directly on or with the diaphragm itself, yet since with devices of this character involving the exertion of considerable power 80 the wear on the diaphragm would be excessive, it is better to provide the diaphragm with a member to serve as a wear piece in such engagement or impact. This member may be, and preferably is, rigid with the dia- 85 phragm itself and participating in its movement. Such movements may be imparted by a lost motion connection, such as shown in Figs. 3 and 4, or by positive connection, such as shown in Fig. 6. In the present em- 90 bodiment of my invention I prefer the lost motion connection shown in Figs. 3 and 4. In said figures the diaphragm is provided with a member for engagement in such connection, this member consisting of an ear 40 95 provided with a screw shank 41 and formed with a shoulder 42 is rigidly secured to the center of the diaphragm by lock nuts 43, screwed down upon the diaphragm, to clamp the same against shoulder 42. This ear is 100 provided with a transverse pin 44 which plays in slots 45 in the bifurcated head 46 of the driving member, 6. This element 6 is a thrust member provided toward its outer end with rigid unyielding surfaces which engage with similar surfaces carried by the dia- 105 phragm member. In the structure of Figs. 3 and 4, 6 is a thrust member in its outward movement and a tension member in its inward movement, and is the equivalent of the 110 articulated thrust member formed by 6 and 8 in Fig. 1.

It is obvious that a mere reversal of this arrangement, either as to the slot and pin or as to the bifurcation, would not involve 115 departure from the spirit of my invention, but the arrangement shown has the advantage that it puts the greatest possible proportion of the weight and of the wear on the driving member rather than on the dia- 120 phragm member, the male engaging members being from the nature of things, less massive in design for equal strengths than the female members. The pin 44 may be easily renewed whereas a worn slot in 45 125 would require an entirely new part and unless made undesirably heavy the wear would be very rapid.

By reason of the comparatively large amount of power available the diaphragm 130

may be made of relatively great diameter, stiffness and amplitude of vibration. It may be clamped and may be put under buckling stress in one direction or it may be a 5 plane sheet arranged to be normally free from such stress. With a 6 inch diaphragm the amplitude of vibration may be $1/32$ to $3/32$ of an inch. These figures are merely 10 illustrative of one possible set of proportions. In practice wide variations are possible.

The lost motion connection is preferably used in connection with a diaphragm having only one normal position of rest, as for instance, a plane diaphragm preferably under no stress though it may be permanently buckled in one direction. The arrangement will be such that one end of the slot 45 will engage the pin 44 and forcibly displace the 20 diaphragm in one direction from its normal position, bringing it back again to normal, then after a slight interval the other end of the slot will engage the pin 44 and forcibly displace and restore the diaphragm from 25 normal, in the opposite direction.

With the tight connection shown in Fig. 6, the movements of the diaphragm are forced and the crank throw and the amplitude of vibration of the diaphragm are equal. In certain cases a useful, though less efficient signal or alarm, may be produced by so selecting the area of the diaphragm and distribution of stresses thereupon that the forced movement at the center thereof will cause semi-independent elastic vibrations localized or distributed in zones about the rigidly secured center and between it and the periphery. A large diaphragm, especially if thin or of less resilient material, is likely to vibrate in 40 this way when the driver is operated at very high speeds, so as to force the main central portions of the diaphragm more rapidly than the movement can be transmitted to the other vibratory portions more remote from 45 the center.

By applying power to the vibrating diaphragm mechanically in accordance with my present invention, I am enabled to select the material of such diaphragm with a view 50 solely to securing the elastic qualities and acoustic properties most desirable in such a member without reference to the electromagnetic qualities which must be considered where the power is to be applied magnetically. I may make the diaphragm of any desired diameter and thickness and of any desired quality of elastic material, as, for instance, soft iron, spring steel, wood, etc.

Where the material selected is sufficiently 60 elastic and durable the pin connection 44^a (Fig. 6) may be dispensed with and connections such as shown in Figs. 7 and 8 may be employed. In Fig. 7 link 6 is clamped directly to the diaphragm thus causing a certain amount of angular flexure thereof. The

amount of such flexure will depend upon the throw of the crank and the length of the link 6 and it may be made an important factor or indeed in some cases the sole factor in the production of the sound. Ordinarily, however, the right-line movement of the diaphragm center given by the structures of Figs. 3, 4, 8, and 9 is preferable as giving wholly normal vibrations. By use of cone or edge clamping members such as shown in Fig. 8 the annular flexure may be almost entirely avoided.

By spacing apart the engaging surfaces of the arrangements of Figs. 7 and 8, a lost motion connection is produced which may be 80 proportioned and utilized after the manner described for such connections with reference to Figs. 4 and 5. This spacing is not specifically shown as it may, and usually would, be too small to be shown without exaggeration. A mere loose fit of the diaphragm-engaging members is sufficient for this purpose.

In Fig. 9, I have shown the disk 15 formed with cam projections 54 arranged to engage 90 a suitable surface 55 on the diaphragm 5, to forcibly displace the latter in one direction without the necessity of a separate reciprocating member. The use of cams in this way permits of a lost motion engagement due 95 to the abrupt radial faces on the back side of the cam, which permit the free elastic return of the diaphragm at its own natural rate.

In practice the design and proportion of parts may vary widely from those shown in 100 the drawing and in making such variations it will generally be advisable to avoid too great mass or weight in the design of parts carried by the diaphragm and also of reciprocating parts such as the link 6. If the 105 speed of rotation is extremely high, the latter member if too heavy may have a serious pounding effect in directions parallel both to the plane of the diaphragm 5 and to the plane of the disk 15. This is further undesirable, in most cases, as tending to impart 110 too much lateral component to the force exerted upon pin 44.

In operating any of the various forms of my invention, the rate or frequency of the 115 movements forced upon the diaphragm by the rotary driving member or by the reciprocating driving member, may be independent of the natural frequency of free vibration of the diaphragm, the diaphragm being 120 given a positive or forced drive, but great resonant sound effect with small expenditure of power will be attained when the forced movement and the natural movement are of the same frequency.

With the tight coupling of driving member and diaphragm such as shown in Figs. 6, 7 and 8, the weight or inertia of the reciprocating driver is in effect a load upon the diaphragm, at all speeds below that correspond- 130

ing to the natural rate of vibration of the diaphragm, when free or unloaded. With a given diaphragm, as with any other elastic vibrator, the rate of vibration is dependent 5 on the elasticity and on the mass of metal to be moved, or its inertia, and with the structure of Figs. 6, 7, and 8 where there is no play between the diaphragm and driver, when the parts are in a position of rest, the 10 inertia of the diaphragm, or the opposition to vibration, is increased by an amount corresponding to the mass of the driving parts since in order to move in vibration, the center of the diaphragm must take with it the 15 attached parts of the driver. But where the driver is itself kept in reciprocating motion, if the reciprocation corresponds to the natural frequency or rate of the diaphragm then the latter behaves as if unloaded and free to 20 move normally. At any lower rate of vibration, the driver constitutes a load. If the driver be speeded up sufficiently, this load will be taken off from the diaphragm in accordance with the increase of speed. The 25 efficiency will therefore, in general, be greater where the speed of the driver is equal to the natural free period or rate of movement of the free diaphragm. These considerations are of practical importance in connection with diaphragms having a natural 30 fundamental rate of vibration corresponding to the lowermost audible notes because the use of a crank imposes practical limitations as to the rate of the forced impulses. The 35 limit is higher in the case of a construction like that of Fig. 9 because the periphery of the disk 15 may be greatly increased and the number of cams 54 greatly multiplied, but in this case, the coupling is loose and the rate 40 of positive outward displacement of the diaphragm is necessarily limited by the time required for the elasticity of the diaphragm to bring it back into position to be again forced outwardly. In this case, also, the 45 full swing of the diaphragm can only be attained where the cam contacts are separated by intervals sufficient to permit the diaphragm to effect its elastic return, and where the cam contacts occur more frequently than 50 the natural period of free elastic vibration of the diaphragm, the amplitude of the movement will be cut short. Hence, it will be understood that while the specific form of cam with an abrupt shoulder on the back 55 side thereof will always permit a high velocity elastic return of the diaphragm, no matter how slow the outward movement may be, nevertheless, in this case also, the best result will be attained where the times and velocities of the cam forcing movements in one direction are harmonized with the times and velocities of the free elastic return.

In the case of the loose link coupling shown in Figs. 3 and 4, the same principles apply. 60 It will be obvious that the operation of this

device may be very much the same as that of the cam, except that a forcing impulse may be applied once per revolution, either on the outgoing thrust movement or on the incoming tension movement, or, if desired, both the outgoing thrust and the incoming tension impulses may be applied so that part of the movement in each direction is forced. In either case, the movement is partly forced and partly free, so that the best operation is obtainable by harmonizing the time and velocities of the forced part of the movement of the diaphragm with the natural times and velocities of the free part of the movement thereof. 70

In all of the above cases of partly forced and partly free movements, if a horn or resonator is used having a pronounced natural frequency, the natural vibratory movements of the diaphragm will tend to harmonize with the natural frequencies of the horn, so that within limits, the natural frequencies of the diaphragm become the same as the natural frequency of the horn. This is of particular value in connection with a friction or electric 90 motor drive where the speed is free to vary proportionally to the work done, since with such motive power, the displacement tends to set itself in synchronism or harmony with one of the natural resonant frequencies of the 95 device, so that in turning on or turning off the motive power, the note tends to dwell at one natural frequency until the power increases to a point where it can jump to the next natural frequency. 100

The resonant qualities of the horn and the natural periodicities of the diaphragm may be harmonized by making the fundamental or the prominent harmonic of the one correspond to a fundamental or a harmonic of the other. 105

In many cases it will be found sufficient to select a diaphragm of large diameter and force thereon a desired frequency independent of its natural period, the latter being suppressed. In such case the forced periodicity may correspond to a fundamental or a harmonic of the horn. If a prominent harmonic of the diaphragm be in accord with a natural period of the horn, the forced periodicity may be arbitrarily selected without particular reference to the period of either the horn or the diaphragm. 115

The crank and link are specially adapted for forcing transverse movement of any 120 sound producing or vibratory member regardless of whether the forced movements are or are not in accord with the natural frequency of the diaphragm vibratory member, because the throw of the crank is usually extremely small as compared with the length of the link, so that the right line movement of the end of the link varies almost exactly according to the law of the sine, and hence any movement imparted thereby to a sound 125 130

generating surface is substantially sinusoidal and particularly adapted for periodic movements in which elasticity and inertia are factors.

5 Certain of my claims herein are broad enough to cover the cam arrangement for vibrating the diaphragm as shown in Fig. 9 and also the rotary electric motor drive explained in connection with Fig. 2 but the 10 more specific claims hereof are directed to the crank and link arrangement for vibrating the diaphragm and to the friction drive shown in Fig. 1. The cam of Fig. 9 is included illustratively as an alternative form 15 in my application, Serial No. 373,946, but the specific claims therefor are found only in my divisional application Serial No. 457,710, which said application also contains broad claims for the rotary electric motor driving 20 arrangement shown in Fig. 2 hereof.

I claim:

1. In an alarm or signaling apparatus of the class described, a horn or resonator and a diaphragm in combination with a shaft, a 25 member presenting a bearing surface placed eccentrically of and rotated from said shaft, and a thrust member driven by said eccentric surface and arranged to forcibly displace said diaphragm in a direction normal to the surface thereof, together with high-speed means 30 for rotating said shaft at a rate sufficient to produce a loud note, substantially as described.

2. In an alarm or signaling apparatus of 35 the class described, a horn or resonator and a diaphragm having a member adapted for engagement in combination with a shaft, a member presenting a bearing surface placed eccentrically of and rotated from said shaft 40 and a thrust member engaging said eccentric surface and adapted to cause positive engagement with and positive displacement of said diaphragm member in one period of the motion of the diaphragm while permitting 45 free movement of such diaphragm in another period of said motion.

3. In an alarm or signaling device of the 50 class described, a horn or resonator, a diaphragm, a rotary member and high-speed means for rotating said rotary member, in combination with a body rigid in the line of motion and adapted to apply the power of 55 said rotary member to a diaphragm element in such manner as to cause a positive displacement of the diaphragm in one period of motion and permit a free movement in another, said parts being so relatively dimensioned, proportioned, and arranged as to cause a plurality of rotations of said rotary 60 member to be necessary to cause an audible note to be emitted by the diaphragm.

4. In an alarm or signaling device of the 65 class described, a horn or resonator, a diaphragm, a rotary member and high-speed means for rotating said rotary member, in

combination with a body rigid in the line of motion and having a lost motion connection with a diaphragm element, said parts being so relatively dimensioned, proportioned, and arranged as to cause a plurality of rotations 70 of said rotary member to be necessary to cause an audible note to be emitted by the diaphragm.

5. In an alarm or signal of the class described, a horn or resonator, a diaphragm 75 and a rotary shaft arranged with its axis approximately parallel to the diaphragm, in combination with means for applying the power of the shaft to vibrate the diaphragm, said means including a member eccentrically 80 pivoted to the shaft for movement in a plane at right angles to the shaft and diaphragm, said means being provided toward its outer end with a hard and unyielding surface adapted to strike against an element of the 85 diaphragm.

6. In an alarm or signal of the class described, a horn or resonator, a diaphragm and a rotary shaft arranged with its axis approximately parallel to the diaphragm, in 90 combination with means for applying the power of the shaft to vibrate the diaphragm, said means including a member secured to the shaft by means adapted to permit movement of said member eccentrically of the 95 shaft axis in a plane perpendicular to the shaft and diaphragm, said means being formed toward its outer end with a hard and unyielding surface adapted to strike against an element of the diaphragm. 100

7. In an alarm or signaling apparatus, a horn or resonator and an air vibrating member, in combination with a reciprocating driving member having a lost motion engagement therewith. 105

8. In an alarm or signaling apparatus, an air vibrating member, in combination with a rotary member and a reciprocating member driven by the latter and having a lost motion connection with said air vibrating member. 110

9. In an alarm or signaling apparatus, a horn or resonator and a diaphragm therefor, in combination with an eccentric and pitman for forcibly displacing the same in one direction and then in the other alternately. 115

10. In an alarm or signaling apparatus, a horn or resonator and a diaphragm therefor, in combination with a reciprocating driving member operatively connected therewith to forcibly move the same and to permit further movement thereof by free elastic vibration. 120

11. In an alarm or signaling apparatus of the class described, a horn or resonator and a diaphragm, in combination with a reciprocating member, provided with a rigid surface adapted to engage the diaphragm and means for reciprocating said member at a rate harmonizing with the rate of elastic vibration of the diaphragm. 125 130

12. In a signaling apparatus for motor conveyances, a horn and a diaphragm closure therefor in combination with a reciprocating member having a lost motion connection 5 with the diaphragm, a rotary member imparting power to said reciprocating member and rotary driving means for said rotary member adapted to derive power from the moving parts of a motor vehicle.
13. In a signaling apparatus for motor conveyances, a horn and a diaphragm closure therefor, said diaphragm carrying a wear piece rigidly secured thereto, in combination with the motor apparatus of said vehicle and 15 a reciprocating member energized from the latter and having a lost motion engagement with said wear piece in the diaphragm.
14. In an alarm or signaling apparatus of the class described, a diaphragm in combination 20 with a rotary member having an eccentric thrust element, a thrust member driven by said eccentric element and having a rigid surface adapted for loose engagement with a diaphragm element to forcibly displace the same in a direction normal to the surface 25 thereof while permitting free elastic movement beyond the forced movement, together with high-speed means for rotating said shaft at any desired rate corresponding to the frequency of the fundamental of any desired note to be produced.
15. In an alarm or signaling apparatus of the class described, a diaphragm in combination 30 with a rotary member having an eccentric bearing element, a thrust member driven by said eccentric element and having a rigid surface adapted for loose engagement with a diaphragm element to forcibly displace the same in a direction normal to the 35 surface thereof while permitting free elastic movement beyond the forced movement, together with high-speed means for rotating said shaft at such rate as to cause said forcible displacements to harmonize with the loose or free elastic movement of the diaphragm.
16. In an alarm or signaling apparatus of the class described, a horn or resonator and a diaphragm, in combination with a rotary member and diaphragm actuating means 40 actuated thereby and adapted to positively displace said diaphragm in one direction and then to permit elastic movement thereof, and high-speed means for driving said rotary member at such rate that the displacements 45 and the elastic movements correspond to a frequency of said horn or resonator.
17. In an alarm or signaling apparatus of the class described, a diaphragm in combination 50 with a rotary member and diaphragm actuating means actuated thereby and designed and arranged to positively displace said diaphragm in one direction, and high-speed means for driving said rotary member at such speed that the frequency of displace- 55
- ments harmonize with the natural elastic 60 movements of the diaphragm.
18. In an alarm or signaling apparatus of the class described, a diaphragm in combination with a reciprocating member for positively displacing the diaphragm in a direction perpendicular to its surface and means for reciprocating said member at a rate synchronizing with the elasticity of the diaphragm. 65
19. In an alarm or signaling apparatus of the class described, a diaphragm in combination 70 with a rotary driving member, and means actuated thereby and arranged to positively bend the central portions of said diaphragm in one direction and then to permit free movement thereof, together with high-speed means for driving said rotary member at a speed sufficient to effect said movements at velocities determined by and harmonizing with a natural frequency of 80 said device.
20. In an alarm or signaling apparatus of the class described, a diaphragm in combination 85 with a rotary member having a member presenting a bearing surface, placed eccentrically, and tension and thrust connections driven by said eccentric member, adapted to engage and positively displace the diaphragm in a direction normal to the surface thereof, together with high-speed 90 means for rotating said rotary member so as to displace said tension and thrust connections at a rate corresponding to the frequency of the fundamental note to be produced, substantially as described. 95
21. In an alarm or signaling apparatus of the class described, a diaphragm in combination 100 with a rotary member having a member presenting a bearing surface, placed eccentrically, tension and thrust connections driven by said eccentric member and loosely engaging a diaphragm member to positively displace the diaphragm in a direction normal to the surface thereof and to permit free elastic movement thereof, together with high-speed means for rotating said rotary member at such rate as to cause displacements to occur at a frequency determined 105 by the rate of loose or free elastic movement of the diaphragm. 110
22. In an alarm or signaling apparatus of the class described, a diaphragm in combination 115 with a rotary member having a member presenting a bearing surface, placed eccentrically, and a tension member driven by said eccentric member, adapted to engage and positively displace a diaphragm member in a direction normal to the surface of the diaphragm, together with high-speed means for rotating said rotary member at a rate 120 corresponding to the frequency of the fundamental note to be produced, substantially as described. 125

23. In an alarm or signaling apparatus of the class described, a diaphragm in combination with a rotary member having a member presenting a bearing surface, placed 5 eccentrically, a tension member driven by said eccentric member and loosely engaging a diaphragm member to positively displace the diaphragm in a direction normal to the surface thereof and to permit free elastic 10 movement thereof, together with high-speed means for rotating said rotary member at such rate as to cause displacements to occur at a frequency determined by the rate of loose or free elastic movement of the dia- 15 phragm.

24. In an alarm or signaling apparatus of the class described, a horn or resonator and a diaphragm, in combination with a rotary member means actuated by said rotary 20 member adapted to cause bodily movement of said diaphragm on both sides of normal by positively displacing the same in one direction and then permitting elastic movement thereof, and high-speed means for 25 driving said rotary member at such rate that the displacements and the elastic movements harmonize with a natural frequency of the device.

25. In an alarm or signaling apparatus of the class described, a diaphragm in combination 30 with crank and link arranged to vibrate said diaphragm alternately on both sides of normal, and means for rotating said crank at a rate sufficient to force upon said dia- 35 phragm a movement of high velocity, great amplitude, and of frequency sufficient to thereby generate a loud note, as and for the purpose described.

26. In an alarm or signaling apparatus of the class described, a diaphragm in combination 40 with a crank and link arranged to vibrate said diaphragm in a direction perpendicular to its surface at a rate sufficient to generate an audible note.

45 27. The method of generating an alarm note of desired pitch and amplitude by means of an elastic diaphragm which comprises periodically applying and removing a positive outward thrust to said diaphragm, dur- 50 ing its outward vibratory movements, said periodicity of application being at intervals corresponding approximately to the natural times of outward movement in the free elastic vibrations of said diaphragm.

55 28. The method of generating an alarm note of desired pitch and amplitude by means of an elastic diaphragm which consists in positively and periodically applying and removing an outward thrust and an inward tension to said diaphragm, said periodicity 60 of application corresponding approximately to the natural time of movement in the free elastic vibrations of said diaphragm.

29. In the generation of alarm notes of de- 65 sired pitch and amplitude, the method of

amplifying the vibrations of a diaphragm which comprises mechanically and positively forcing a portion of each vibration while allowing another portion of such vibration to be free.

70

30. In a signaling apparatus for motor conveyances, a case, a horn or resonator secured thereto, a diaphragm and a crank and link driving means therefor within said case, in combination with a driving connection for 75 the latter extending outside said case and including a shaft provided with a non-positive or slip connection with a source of power.

31. In a signaling apparatus for motor conveyances, a case, a horn or resonator se- 80 cured thereto, a diaphragm and a rotary driving member therefor within said case, in combination with a driving connection for the latter extending outside said case and in- cluding a shaft provided with a non-positive 85 or slip connection with a source of power.

32. In a signaling apparatus for motor conveyances, a horn or resonator secured to a suitable case, a diaphragm and mechanical driving means therefor within said case, in 90 combination with a driving connection for the latter extending outside said case and in- cluding a shaft provided with a non-positive or slip connection with a source of power.

33. In a signaling apparatus for motor 95 conveyances, a horn or resonator secured to a suitable case, a diaphragm and a rotary driving member therefor within said case, in combination with a driving connection for the latter extending outside said case and 100 including a flexible shaft, a friction wheel, and means for throwing said wheel into and out of driving relation with a motor mechanism of said conveyance.

34. In a signaling apparatus for motor 105 conveyances, a horn or resonator secured to a suitable case, a diaphragm and a crank and link driving means therefor within said case, in combination with a driving connection for the latter extending outside said case and in- 110 cluding a flexible shaft, a friction wheel, and means for throwing said wheel into and out of driving relations with a motor mechanism of said conveyance.

35. In a signaling apparatus for motor 115 conveyances, a horn or resonator secured to a suitable case, a diaphragm and mechanical driving means therefor within said case, in combination with a driving connection for the latter extending outside said case and in- 120 cluding a flexible shaft, a friction wheel, a bearing therefor and a slid able support for said bearing controlled by the operator for throwing said wheel into and out of driving relation with a motor mechanism of said con- 125 veyance.

36. In a signal or alarm of the class de- 130 scribed, an elastic diaphragm, in combina- tion with means for bodily displacing the central portions of said diaphragm so as to

put them under elastic stress and for removing said displacing means fast enough to permit a free elastic reverse movement of said diaphragm.

5 37. The method of producing an alarm or signal of the class described which comprises mechanically and positively forcing a diaphragm in repeated outward vibration beyond its normal position to a predetermined 10 position at such a velocity as to cause further

outward movement of the diaphragm in the same direction by inertia against increasing elastic stress.

Signed at New York city in the county of New York, and State of New York. 15
